Application December 2, 1955, Serial No. 550,733

Claims priority, application Canada December 13, 1954

16 Claims. (Cl. 103—234)

This invention relates to a method of conveying a liquid through a pipeline, and to apparatus for carrying out this method.

One of the primary commercial uses of the invention will be in the conveyance of oil or oil products such as gasoline, and for this reason the invention will be chiefly exemplified below with reference to such products which will be referred to hereinafter generally as "oil," although, as will be more fully explained later, the invention in its broadest aspect is applicable to the conveyance of any liquid suitable for passage through a pipeline. The term "pipeline" is similarly intended to denote any conduit however long or short it may be.

In the past the conveyance of oil through pipelines has required pumping machinery to supply the necessary pressure. The present invention entirely avoids any need for pumps and relies solely on pressure generated on the formation of vapour produced either by heating the oil itself or some other liquid such as water.

In one preferred method of operation expressed in broad terms, the invention consists of a method of conveying a liquid through a pipeline, comprising confining a quantity of the liquid to be conveyed in a closed vessel having an outlet communicating with a lower part of the interior of said vessel and with the pipeline, providing a quantity of vapour under pressure in said vessel above the surface of said liquid whereby to force such liquid through such outlet and through the pipeline, supplying a further quantity of said liquid to a second closed vessel arranged at least in part above the level of said outlet, establishing a first connection between the interior of the first vessel and the interior of the second vessel (advantageously between upper parts of such interiors) whereby to communicate the vapour pressure to said second vessel, establishing a second connection between the interior of said second vessel and the interior of the first vessel (advantageously between lower parts of such interiors) whereby to allow the liquid in said second vessel to flow under gravity into the first vessel, such connections being established before the level in said first vessel falls below the level of said outlet, interrupting said connections to isolate said second vessel from the pressure in the first vessel and continuing to provide a further quantity of vapour under pressure in the first vessel above the surface of the liquid therein.

It is preferred that the vapour employed be a vapour of the liquid or oil being conveyed. For this purpose it is preferred to generate the vapour in the first vessel by heating such vessel sufficiently to cause a portion of the liquid therein to evaporate and form a body of vapour under pressure above the surface of such liquid, this application of heat to the first vessel being maintained to ensure continuation of this evaporation process each time the first vessel is recharged from the second vessel.

Alternatively, the vapour may be supplied from some external source and may be the vapour of a different liquid. For example, when a heavy oil is being conveyed, the vapour may be steam supplied from a sepa-

2

rate boiler. After its passage into the second vessel on establishment of the connections referred to above, the steam will condense and flow back into the first vessel during the next operation there to be reheated and re-evaporated. This method of operation will be more fully explained below.

The invention also relates to apparatus for carrying out these methods, and one convenient form of such apparatus is illustrated diagrammatically and by way of example in the accompanying drawings, in which:

Figure 1 shows diagrammatically the layout of the apparatus;

Figure 2 is a fragment of the apparatus shown in Figure 1, demonstrating the condition at a later stage in the process; and

Figure 3 is a similar fragment to that of Figure 2, showing the conditions at a further stage in the process.

Figure 4 is a similar fragment to that of Figure 2, showing a modified version of the apparatus;

Figure 5 is another fragment of the apparatus, illustrating a still further modification;

Figure 6 is an enlarged fragmentary view of a float valve for use in the apparatus of Figures 1 to 5; and

Figure 7 is a diagram illustrating a typical control circuit.

The apparatus illustrated consists of a cylindrical discharge vessel 1 having an outlet pipe 2 extending from a point near the bottom thereof, this pipe 2 being connected to a pipeline (not shown). The discharge vessel 1 is otherwise closed except for a pair of passages 3 and 4 which establish connections between such vessel 1 and each of one or several supply vessels 5. In Figure 1 two such supply vessels 5, identical in character, are shown. In practice any required number of such supply vessels 5 may be employed, this depending upon the rate at which such vessels can conveniently be recharged. Only one such supply vessel 5 need be employed if it can be recharged as quickly as the discharge vessel 1 is emptied, as will become more clearly apparent from the subsequent description of the operation of the apparatus.

Each passage 3 extends between an upper part of the discharge vessel 1 and an upper part of a supply vessel 5, a valve 6 whereby communication between the two vessels may be established or interrupted as required being arranged at a convenient point along such passage; while each passage 4 extends between a lower part of the discharge vessel 1 and a lower part of a supply vessel 5, a valve 7 whereby this communication between the two vessels may be established or interrupted as required being arranged at a suitable point in such passage 4. Each supply vessel 5 is otherwise closed except for an inlet passage 8 extending to and fed from a main reservoir tank 9, a valve 10 being arranged in such passage 8 for control of the flow of liquid therethrough.

The discharge vessel 1 is arranged to be heated by a number of burners 11 which may conveniently be fired with oil when oil is the liquid being conveyed. For this purpose a branch pipe 12 is shown extending from the pipe 2 to a tank 13 from which a controlled quantity of oil passes to the burners 11. A non-return valve shown as a simple flap-type valve 14 is provided in the pipe 2.

To consider the operation of this system let it be assumed that initially there is a quantity of oil in the discharge vessel 1 extending up to the level 15 shown in Figure 1 and that the left hand supply vessel 5 contains a further quantity of such oil. The burners 11 are started and they heat the oil in the discharge vessel 1 causing some of the more volatile fractions of such oil to evaporate and form a body of vapour at the top of such vessel 1. The valves 6 and 7 are closed at this time, so that such pressure is contained in the vessel 1. This pressure, which may in practice finally reach a value of

the order of ten atmospheres, acts downwardly on the surface of the oil in the vessel 1 thus causing a quantity of such oil to be discharged along the pipe 2, as indicated by the arrows 16 shown in Figure 2, until an oil level shown at 17 in Figure 2 is reached.

It is possible to detect when this level has been reached visually, but it is preferred to achieve automatic operation by providing some form of level-sensitive means, such as a float. A typical such float-type device 18 is shown in Figure 6 and consists of a tube 32 secured to the side of the discharge vessel 1 and having openings 33 top and bottom so that the level of the liquid inside the tube 32 will be the same as in the body of the vessel 1. A float 34 travels up and down the tube 32 in accordance with the level of the liquid and in its lower position bears on a stop 36 mounted in the centre of a flexible diaphragm 35. On the other side of the stop 36 in a fluid-tight chamber 38 the flexible diaphragm 35 carries an electric contact 37 positioned for co-operation with a spaced stationary electric contact 37'. It will be obvious that when the level of the liquid falls sufficiently for the weight of the float to bear against the stop 36, the diaphragm 35 will be deflected downwardly to cause the contacts 37 and 37' to engage. These contacts are connected to electrical leads 39. This form of float device is conventional. The level sensitive means 18 is connected to a control device 19 (see Figure 1) which is operated to open the valves 6 and 7 of the passages 3 and 4 extending to the left-hand supply vessel 5 when the oil falls to the level 17. Opening these valves causes the vapour under pressure in the discharge vessel 1 to pass into the top of the supply vessel 5. Substantially the same pressure is, of course, also transmitted through the oil into the lower part of the supply vessel 5, so that the pressure throughout the two vessels becomes equalized. Since the vessel 5 is arranged at a level above the discharge vessel 1, the oil in the vessel 5 is now free to flow under gravity into the discharge vessel 1, until the situation illustrated in Figure 3 is achieved with the level of oil in the discharge vessel 1 again near the top of such vessel as shown at 20, the supply vessel 5 having been drained.

In the apparatus illustrated the bottoms of the supply vessels 5 are shown approximately on a level with the top of the discharge vessel 1. If preferred, the supply vessels 5 may be positioned well above the discharge vessel 1 to promote more rapid flow, or on the other hand there may even be rather more overlap between these levels than shown in the drawings. In the latter case, the supply vessels 5 will not be fully emptied until the level of oil in the discharge vessel 1 has fallen somewhat. The essential relationship between these levels is that they should be such that transfer by gravity of at least the bulk of the liquid in the supply vessel 5 into the discharge vessel 1 will take place reasonably quickly and that there will be adequate time available for refilling the supply vessel 5, having regard to the number of such vessels employed.

As soon as the supply vessel 5 is emptied, i.e. the Figure 3 condition has been achieved, the valves 6 and 7 may be reclosed and for this purpose further level-sensitive means 21 structurally similar to the level-sensitive means 18 may be provided in each such supply vessel 5. Alternatively, since it is really the level in the discharge vessel 1 that requires precise control, the valves 6 and 7 may be closed in accordance with the operation of level-sensitive means 22 in the vessel 1. Figure 7 shows diagrammatically a typical arrangement of control device 19 operated by the level sensitive means 18 and 22. In this case the control device 19 consists of a valve opening relay 40 and a valve closing relay 41. Electric power is supplied through terminals 42 and 43. Through electric leads 39 the energizing coil of the relay 40 is connected across the supply terminals 42 and 43 in series with the contacts in the level-sensitive means 18. In a

similar manner the valve closing relay 41 is connected in series with the contacts in the level-sensitive means 22, across these same supply terminals 42 and 43. Thus, when the level falls to the position shown in Figure 2 and the contacts in the level-sensitive means 18 are closed, the relay 40 will be energized thus closing its normally open contacts and connecting the lead 44 to the terminal 43. Each of the valves 6 and 7 which are conventional motor-driven valves have three electric power leads. The central lead 45 is at all times connected to the power supply terminal 42 and the two outside leads 44 and 46 are connected intermittently as required. When the lead 44 is energized the motors in the valves 6 and 7 are operated to open the valves; when the lead 46 is energized by connection to the terminal 43 the motors in the valves 6 and 7 are driven in the reverse direction to close the valves 6 and 7. It will thus be seen that, when the level-sensitive means 18 operates the relay 40, the lead 44 is energized and the valves 6 and 7 are opened. When the level in the discharge vessel 1 has risen to submerge the level-sensitive means 22, the contacts 37 and 37' in such means 22 will deenergize the relay 41 which is shown in Figure 7 in the energized position. This release of the relay 41 closes its contacts to connect the lead 46 to the terminal 43, thus driving the motors in the valves 6 and 7 to close such valves. This is a conventional manner of operating valves in accordance with liquid level changes. If it is preferred to operate the valves 6 and 7 in accordance with the level 30 in a supply vessel 5, then the valve opening and closing relays 40 and 41 can be similarly connected to the level-sensitive means 21 and 23. As soon as the valves 6 and 7 have been closed by one of such control methods, the emptied supply vessel can be recharged by opening 35 the valve 10, the actuation of all these valves 6, 7 and 10 being achieved automatically through the control device 19 in a manner generally similar to that already described in connection with Figure 7. The vapour that passed into the supply vessel 5 through the passage 40 3 will soon become condensed in the colder vessel, thus producing a sub-atmospheric pressure therein which accelerates refilling of such vessel from the main reservoir 9. The valve 10 may finally be reclosed by further level-sensitive means 23 acting through the control device 45 19.

While this refilling operation has been taking place, the discharge vessel 1 has continued to operate in the manner already described, the fresh oil being heated by the burners 11 and the pressure of the vapour formed 50 thereby in the top of such vessel causing the oil to continue to flow out through the pipe 2. Since the rate at which the discharge vessel 1 is emptied will often be greater than the rate at which a single vessel 5 can be recharged with a further quantity of oil from the reservoir 55 9, the second supply vessel 5 is provided, the control device 19 being arranged to operate these vessels alternately. Similarly, if more than two supply vessels are found necessary, they will be operated in sequence.

It is found in practice that there is only a momentary 60 lull in the flow of oil into the pipe 2 on refilling of the discharge vessel 1, the level-sensitive means 18 being adjusted to ensure that an appreciable quantity of oil is left in such vessel to communicate heat to the cold incoming oil. If found necessary, the oil may be subjected to 65 a degree of pre-heating in the supply vessels 5. Moreover, if an especially steady flow of oil in the pipeline is desired, the assembly shown in the drawings may be duplicated, two discharge vessels 1 being provided and arranged to operate out of phase with one another so 70 that one is forcing oil into the pipeline while the other is refilling.

In the apparatus so far described and illustrated it will be observed that the capacity of each supply vessel 5 has been shown as rather less than the capacity of the discharge vessel 1, so that each charge of liquid dis-

pensed from a supply vessel will serve to bring the discharge vessel from the not quite empty condition (Fig. 2) to the not quite full condition (Fig. 1 or 3) bearing in mind that there is a constant outflow of liquid through the pipe 2. Clearly, if the supply vessels were made much smaller than the discharge vessel, more frequent filling of the supply vessels would be required in order to keep the discharge vessel supplied with liquid, although it may in certain cases be found desirable to add small quantities of liquid to the discharge vessel at comparatively frequent intervals. This would prevent the level of liquid in the discharge vessel from rising or falling to the extreme ends of the vessel, but would cause it to oscillate instead between a pair of relatively closely spaced intermediate levels. Such a method of operation reduces the extent of fluctuations of temperature and pressure and, therefore, results in a steadier flow from the outlet pipe. On the other hand, it somewhat complicates the apparatus in that it would be necessary to use a fairly large number of small supply vessels and to provide the means for connecting them in sequence to the discharge vessel.

As mentioned above, the primary application of the invention industrially will be to the conveyance of oil and oil products. It is also anticipated that other industrial products such as molasses may be conveyed by such means. Asphalt is also a product which is sometimes conveyed through pipelines, although it is necessary to mix the asphalt with steam to render it sufficiently fluid to travel through a pipeline.

If the liquid being transported does not include a sufficiently volatile constituent to produce the necessary vapour in the discharge vessel 1, then a separate supply of a vapour may be used. For example, if a heavy oil from which insufficient vapour can be obtained is being conveyed, a separate supply of steam may be fed to the discharge vessel 1 from an auxiliary boiler 30 heated by burners 31, say through a connection such as shown at 24 in Figure 4. This steam will then act similarly to the vapour formed in situ in the method previously described, to force the oil through the pipe 2. When the valves 6 and 7 open, the steam will pass into the supply vessel 5, and the fresh supply of oil will run down into the discharge vessel 1 as before. When the valves have been re-closed, further steam will be supplied through the connection 24; indeed such supply of steam may not have been interrupted. In the meantime the steam that has passed into the supply vessel 5 will condense and will find its way to the bottom of such vessel to pass eventually back to the discharge vessel 1 with the next charge of oil travelling along the pipe 4. This water will not mix with the oil and will be evaporated again by the heat applied to the discharge vessel 1. Thus, a large quantity of the steam will continue to cycle around the apparatus, although some fresh steam will be needed to compensate for the small quantity of water that will be carried over with the oil into the pipe 2. This trapping of the water in the oil may necessitate the provision of means for separating the water from the oil at the receiving end of the pipeline.

The closed circuit type of operation described above is much preferred in most circumstances, because of its conservation of the heat energy imparted to the vapour within the system. Clearly, however, it is not basic to the operation of the system that the vapour allowed to pass from the vessel 1 should enter a supply vessel 5. It could pass to some other condensing vessel, or, in the case of non-toxic vapours, such as steam, it could be allowed to pass to the atmosphere. This modification is illustrated in Figure 5 which shows the portion 3' of the passage 3 on the side of the valve 6 remote from the discharge vessel 1, as open to atmosphere. In this case, the designer of the system would have more freedom in determining the size of the supply vessel or vessels. A supply vessel very much larger than the dis-

charge vessel could then be used, such supply vessel constituting, in effect, the reservoir (the vessel 9' shown in Figure 5). If steam is the vapour concerned, and it is vented to atmosphere, this less efficient but somewhat simplified method of operation in accordance with the invention can be applied either when water is the liquid being conveyed along the pipeline, or alternatively when the steam is being used to force along such pipeline a liquid from which insufficient vapour can be obtained by heating, i.e. the system for pumping heavy oil discussed above.

Thus, in accordance with a further method of operation expressed in broad terms, the invention consists of a method of conveying a liquid through a pipeline, comprising confining a quantity of the liquid to be conveyed in a closed vessel having an outlet communicating with a lower part of the interior of said vessel and with the pipeline, providing a quantity of vapour under pressure in said vessel above the surface of said liquid whereby to force such liquid through such outlet and through the pipeline, supplying a further quantity of said liquid in a second vessel arranged at least in part above the level of said outlet, establishing a passage from the interior of the first vessel whereby to allow the vapor pressure in said first vessel to escape therefrom, establishing a connection between the interior of said second vessel and the interior of the first vessel whereby to allow the liquid in said second vessel to flow under gravity into the first vessel, such passage and connection being established before the level of the liquid in said first vessel falls below the level of said outlet, interrupting said passage and connection to isolate said first vessel and continuing to provide a further quantity of vapour under pressure in the first vessel above the surface of the liquid therein.

It will be observed that by virtue of the invention a very simple form of apparatus has been provided for forcing oil or other liquids through a pipeline. In particular, the apparatus has the merit of avoiding pumping machinery, and, except for the simple valves and level-sensitive control means, it is entirely devoid of moving parts. This simplicity leads to reduced cost of installation and maintenance and greatly reduces the need for skilled supervision. The apparatus does not call for any special features in the construction of the pipeline itself, so that it can be readily fitted to existing installations.

Furthermore, the apparatus is especially convenient when it is desired to clean the pipeline. The most satisfactory method of cleaning a pipeline is to pass steam therealong, and the provision of the heated discharge vessel in the present apparatus renders the generation of such steam a relatively simple matter with the existing installation. A suitable connection 25 (Fig. 1) having a normally closed valve 26 and extending between the upper part of the heated discharge vessel and the pipeline may be provided to facilitate such a cleaning operation.

The heat absorbed by the oil in the discharge vessel is not wasted, since it serves to lower the viscosity of the oil and thus to increase the efficiency of the pipeline. This feature is not in itself new, as it has already been proposed to heat oil prior to its being pumped along a pipeline. Such heat has, however, been provided essentially for the purpose of lowering the viscosity of the oil, and no prior method has employed the pressure of a vapour formed either by heating the oil or other liquid to be conveyed, or by heating an auxiliary liquid, to force the main liquid along the pipeline.

As in conventional pipelines, booster stations may be positioned along a long pipe. Such booster stations may be similar to the basic unit already described or may function merely to add further heat to the oil to maintain its low viscosity. Once the system has been in operation for some time all the parts will have become well heated and less heat will require to be added to maintain

a fast flow of oil. The economies obtained by use of the invention are so extensive that it may even be found practical to bury or lag the pipeline in cold climates in order to conserve the heat imparted to the oil.

It has previously been considered economically necessary to deparaffinate oils rich in paraffin before conveyance through a pipeline to avoid the paraffin deposits that form in the pipe and gradually reduce its diameter. The temperature of operation in accordance with the present invention will normally be sufficiently high, e.g. at 10 least 40° C., to retain the paraffin in liquid state and thus entirely avoid or at least very considerably reduce deposition of paraffin. Even if a certain degree of paraffin deposition is experienced, the simplification in the cleaning of the pipeline afforded by apparatus according to the present invention is expected to avoid the need for such deparaffination of the oil before transportation.

I claim:

1. A method of conveying a liquid through a pipeline, comprising confining a quantity of the liquid to be conveyed in a closed vessel having an outlet communicating with a lower part of the interior of said vessel and with the pipeline, providing a quantity of vapour under pressure in said vessel above the surface of said liquid whereby to force such liquid through such outlet and through the pipeline, supplying a further quantity of said liquid to a second closed vessel arranged at least in part above the level of said outlet, establishing a first connection between the interior of the first vessel and the interior of the second vessel whereby to communicate the vapour pressure to said second vessel, establishing a second connection between the interior of said second vessel and the interior of the first vessel whereby to allow the liquid in said second vessel to flow under gravity into the first vessel, such connections being established before the level of the liquid in said first vessel falls below the level of said outlet, interrupting said connections to isolate said second vessel from the pressure in the first vessel and continuing to provide a further quantity of vapour under pressure in the first vessel above the surface of the liquid therein.

2. A method of conveying a liquid through a pipeline, comprising confining a quantity of the liquid to be conveyed in a closed vessel having an outlet communicating with a lower part of the interior of said vessel, applying heat to said vessel sufficient to cause a portion of the liquid therein to evaporate and form a body of vapour under pressure above the surface of said liquid whereby to force such liquid through such outlet and through the pipeline, supplying a further quantity of said liquid to a second closed vessel arranged at least in part above the level of said outlet, establishing a first connection between the interior of the first vessel and the interior of the second vessel whereby to communicate the vapour pressure to said second vessel, establishing a second connection between the interior of the second vessel and the interior of the first vessel whereby to allow the liquid in said second vessel to flow under gravity into the first vessel, such connections being established before the level of the liquid in the first vessel falls below the level of said outlet, interrupting such connections to isolate the second vessel from the pressure in the first vessel and continuing to apply such heat of the first vessel.

3. A method of conveying a liquid through a pipeline, comprising confining a quantity of the liquid to be conveyed in a closed vessel having an outlet communicating with a lower part of the interior of the said vessel and with the pipeline, heating a second liquid in a boiler sufficiently to cause a portion of such second liquid to evaporate and form a body of vapour pressure, feeding a quantity of such vapour of the second liquid into said vessel above the surface of the first liquid therein whereby to force said first liquid through such outlet and through the pipeline, supplying a further quantity of said first liquid to a second closed vessel arranged at least

in part above the level of said outlet, establishing a first connection between the interior of the first vessel and the interior of the second vessel whereby to communicate the vapour pressure to said second vessel, establishing a second connection between the interior of the second vessel and the interior of the first vessel whereby to allow the liquid in said second vessel to flow under gravity into said first vessel, such connections being established before the level of the liquid in the first vessel falls below the level of said outlet, interrupting said connections to isolate said second vessel from the pressure in the first vessel and continuing to provide a further quantity of said vapour under pressure to the first vessel above the surface of the liquid therein.

5 4. A method as claimed in claim 1, including the step of recharging said second vessel with a further quantity of said liquid.

5 5. A method as claimed in claim 1, wherein said first connection extends to the interior of the second vessel from an upper part of the interior of the first vessel.

6 6. A method according to claim 1, wherein said first connection extends, from an upper part of the interior of the first vessel to an upper part of the interior of the second vessel.

25 7. A method according to claim 1, wherein said second connection extends between the interior of the first vessel and a lower part of the interior of the second vessel.

8 8. A method according to claim 1, wherein said second connection extends from a lower part of the interior of the second vessel to a lower part of the interior of the first vessel.

9 9. A method according to claim 3 wherein said second liquid is water.

30 10. A method of conveying a liquid through a pipeline, comprising confining a quantity of the liquid to be conveyed in a closed vessel having an outlet communicating with a lower part of the interior of said vessel and with the pipeline, providing a quantity of vapour under pressure in said vessel above the surface of said liquid whereby to force such liquid through such outlet and through the pipeline, supplying a further quantity of said liquid to a second closed vessel arranged at least in part above the level of said outlet, establishing a first connection between the interior of the first vessel and the interior of the second vessel whereby to communicate the vapour pressure to said second vessel, establishing a second connection between the interior of the second vessel and the interior of the first vessel whereby to allow the liquid in said second vessel to flow under gravity into the first vessel, such connections being established before the level of the liquid in said first vessel falls below the level of said outlet, interrupting said connections to isolate said second vessel from the pressure in the first vessel, continuing to provide a further quantity of vapour under pressure in the first vessel above the surface of the liquid therein whereby to continue to force it through such outlet and through the pipeline, supplying a still further quantity of said liquid to a third closed vessel arranged at least in part above the level of said outlet, establishing a first connection between the interior of the first vessel and the interior of the third vessel whereby to communicate the vapour pressure to said third vessel, establishing a second connection between the interior of said third vessel and the interior of the first vessel whereby to allow the liquid in said third vessel to flow under gravity into the first vessel, such connections being established before the level of the liquid in the first vessel falls below the level of said outlet, interrupting said connections, to isolate said third vessel from the pressure in the first vessel and continuing to provide a further quantity of vapour under pressure in the first vessel above the surface of the liquid therein.

40 11. The combination of a pipeline and apparatus for conveying a liquid therethrough, said apparatus comprising

45 12. The combination of a pipeline and apparatus for conveying a liquid therethrough, said apparatus comprising

50 13. The combination of a pipeline and apparatus for conveying a liquid therethrough, said apparatus comprising

55 14. The combination of a pipeline and apparatus for conveying a liquid therethrough, said apparatus comprising

60 15. The combination of a pipeline and apparatus for conveying a liquid therethrough, said apparatus comprising

65 16. The combination of a pipeline and apparatus for conveying a liquid therethrough, said apparatus comprising

70 17. The combination of a pipeline and apparatus for conveying a liquid therethrough, said apparatus comprising

75 18. The combination of a pipeline and apparatus for conveying a liquid therethrough, said apparatus comprising

ing a first closed vessel having at a lower part thereof an outlet communicating with the pipeline, means operatively associated with said vessel for providing vapour in said vessel, a second closed vessel arranged at least in part above the level of said outlet, a first connecting passage extending between an upper part of the interior of the first vessel and the interior of the second vessel, a second connecting passage extending between the lower part of the interior of the second vessel and the interior of the first vessel, flow controlling valves one in each of said passages, and means for determining the level of liquid in the first vessel, such liquid level determining means being operatively connected to said valves to open said valves when said level attains a predetermined minimum level higher than that of said outlet and to close said valves when said level attains a predetermined maximum level.

12. The combination of claim 11, including an inlet passage connecting the second vessel with a reservoir, a third valve controlling flow along said inlet passage, and means sensitive to the level of liquid in said second vessel effective to open said third valve when the level in said second vessel attains a predetermined low level and effective to close said valve whenever said level attains a predetermined higher level.

13. The combination of a pipeline and apparatus for conveying a liquid therethrough, said apparatus comprising a first closed vessel having at a lower part thereof an outlet communicating with the pipeline, means for heating said vessel, a second closed vessel arranged at least in part above the level of said outlet, a first connecting passage extending between an upper part of the interior of the first vessel and the interior of the second vessel, a second connecting passage extending between the lower part of the interior of the second vessel and the interior of the first vessel, a flow controlling valve in each of said passages, and means for determining the level of liquid in said first vessel, such liquid level determining means being operatively connected to said valves to open said valves when said level attains a predetermined minimum level higher than that of said outlet and to close said valves when said level attains a predetermined maximum level.

14. The combination of a pipeline and apparatus for conveying a liquid therethrough, said apparatus comprising a closed vessel having at a lower part thereof an outlet communicating with the pipeline, a boiler for heating a second liquid, means for supplying a quantity of vapour of said second liquid formed in said boiler to said vessel, a second closed vessel arranged at least in part above the level of said outlet, a first connecting passage extending between an upper part of the interior of the first vessel and the interior of the second vessel, a second connecting passage extending between a lower part of the interior of the second vessel and the interior of the first vessel, a flow controlling valve in each of said passages, and means for determining the level of liquid in the first vessel, such

liquid level determining means being so arranged as to be operative to open said valves when said level attains a predetermined minimum level higher than that of said outlet and being so arranged as to be operative to close said valves when said level attains a predetermined maximum level.

15. A method of conveying a liquid through a pipeline, comprising confining a quantity of the liquid to be conveyed in a closed vessel having an outlet communicating with a lower part of the interior of said vessel and with the pipeline, applying heat to said vessel sufficient to cause a portion of the liquid therein to evaporate and form a body of vapour under pressure above the surface of said liquid whereby to force such liquid through such outlet and through the pipeline, supplying a further quantity of said liquid in a second vessel arranged at least in part above the level of said outlet, establishing a passage from the interior of the first vessel whereby to allow the vapour pressure in said second vessel to escape therefrom, establishing a connection between the interior of said second vessel and the interior of the first vessel whereby to allow the liquid in said second vessel to flow under gravity into the first vessel, such passage and connection being established before the level of the liquid in said first vessel falls below the level of said outlet, interrupting said passage and connection to isolate said first vessel and continuing to provide a further quantity of vapour under pressure in the first vessel above the surface of the liquid therein.
16. The combination of a pipeline and apparatus for conveying a liquid therethrough, said apparatus comprising a first closed vessel having at a lower part thereof an outlet communicating with the pipeline, means for heating said vessel, a second vessel arranged at least in part above the level of said outlet, a first passage extending to atmosphere from an upper part of the interior of the first vessel, a connecting second passage extending between a lower part of the interior of the second vessel and the interior of the first vessel, flow controlling valves one in each of said passages, and means for determining the level of liquid in the first vessel, such liquid level determining means being operatively connected to said valves to open said valves when said level attains a predetermined minimum level higher than that of said outlet and to close said valves when said level attains a predetermined maximum level.
